CONTROL DEVICE

Russell A. Winborne, Oak Park, and Raymond L. Coultrip, Waukegan, Ill., assignors to Edison General Electric Appliance Company, Inc., Chicago, Ill., a corporation of New York

Application November 1, 1939, Serial No. 302,390

11 Claims. (Cl. 200—139)

This invention relates to a control device and more particularly to a control device constructed and arranged to be used as an over-temperature release switch for electrical equipment such as an electric liquid heater.

While the new and improved over-temperature release switch of this invention will be described in connection with an electric hot water heater, it is to be understood that it is not intended to limit this invention to such an application since it may be applied to other types of apparatus and certain features of our new and improved switch may be applied to control devices in general.

In an electric hot water heater it is customary to provide one or more temperature responsive devices which operate to maintain the temperature of the liquid at a predetermined value. With such installations it is advisable to provide some form of over-temperature release switch which will act as a positive safety device to prevent over heating in case of failure of the main control devices. Such an over-temperature safety device should be constructed so that it will not automatically reclose at normal ambient temperatures encountered during use but may be manually reclosed. Furthermore, such a device should be constructed and arranged so that it has a wide operating contact gap so as to lessen the possibility of flashover, and, in order to insure that the release temperature for which the device is set will not change over a long period of time, the device must be simple yet sturdy and must have low stressed operating members. Other considerations are that the contacts must break positively and the material selected must stand up over a long period of time without corrodung.

It is the object of this invention to provide an overtemperature release switch for an electric heater which incorporates all of the above requirements so that a sturdy, compact control device is obtained which maintains its calibration over a long period of time and which is relatively simple in construction and may be manufactured at low cost.

It is a further object of this invention to provide a control device suitable for an over-temperature release switch so constructed and arranged that when the control is actuated in response to a predetermined high temperature it will remain in the open circuit condition for all normal ambient temperatures until manually reset.

It is a further object of this invention to provide in an over-temperature release switch an improved construction and arrangement in which, to obtain a positive break of the contacts, the small movements of the temperature responsive element of the device are not transmitted directly to the contact structure and the

contact structure is moved only after the temperature responsive element has accelerated a predetermined amount so that it imparts a kick to the transmitting means between the element 5 and the movable contact assembly.

Further objects and advantages of this invention will appear as the accompanying description proceeds and the features of novelty which characterize this invention will be pointed out 10 with particularity in the claims appended to and forming a part of this specification.

For a more complete understanding of this invention, reference should be had to the accompanying drawing in which Fig. 1 is an elevation partly in section of a liquid heater to which the over-temperature release switch of this invention is applied; Fig. 2 is a top view of the new and improved control device of this invention; Fig. 3 is a sectional view taken on the line 3—3 20 of Fig. 2 and looking in the direction of the arrows; Fig. 4 is a plan view partly in section of the control device of this invention with the cover and fixed contact structure removed; and Fig. 5 is a circuit arrangement showing the electrical connections to the over-temperature switch when it is applied to a liquid heater having two heater elements and separate temperature responsive control devices for each heater element.

Referring to Fig. 1, the control device of this invention has been shown as applied to a liquid heater and in particular a water heater having a tank 10 in which is located a pair of heating elements 11 and 12, the energization of which 25 is controlled by a pair of suitable temperature responsive devices 13 and 14 mounted on the wall of the tank 10. Mounted on the wall of the tank 10 near the top thereof is the over-temperature release switch indicated generally by the numeral 15. The tank 10 is provided with suitable inlet and outlet connections 16 and a casing 17 is provided around the tank, suitable insulating material 18 being located between the casing and the tank. It is to be understood that while this 30 invention will be discussed with reference to a liquid heater, it has more general application and may be used as an over-temperature release switch for other types of appliances.

The control device of this invention is shown 35 in detail in Figs. 2, 3 and 4. Referring particularly to Figs. 3 and 4, it will be observed that the control device includes a base plate 19 made from a good heat conducting material such as brass nickel-plated in order to prevent corrosion. 40 Provided near the lower end of the base plate 19 is a bracket 20 made of a similar material on which is firmly secured one end of a temperature responsive element 21. The temperature responsive element comprises two strips of metal 45 welded together along their lengths and having 50

dissimilar thermal coefficients of expansion. In the particular embodiment of our invention illustrated, the strips of metal comprise strips of invar and nickel chrome steel. The bimetallic strip 21 is secured to the bracket 20 by means of a plurality of rivets 23. The component elements of the bimetal strip are arranged so that upon an increase in temperature the bimetal will deflect to the left as viewed in Fig. 3.

In order to cause the bimetallic element 21 to move quickly and with a snap-action when the predetermined operating temperature has been attained, a pivotally mounted resilient member 24 is arranged to bear on the free end thereof. The resilient member 24 comprises a coil spring element 25 which lies between two cup-shaped members 26 and 27. The cup-shaped member 26 is provided with a slot or depression 28 into which is inserted the free end of the bimetal strip 21 which is shaped in the form of a knife-edge 29. The cup-shaped member 27 is provided with an indentation 30 which is adapted to receive the rounded end 31 of an adjusting screw 32. By means of this latter construction, the resilient member 24 is adapted to pivot about the end of the adjusting screw. The adjusting screw 32 is secured in a bracket 33 firmly attached to the base plate 19 by means of rivets 34 and a lock nut 35 is provided on the adjusting screw 32 for locking it in its adjusted position.

In assembling the elements described thus far, the bimetal element 21 is mounted on its support and the adjusting screw 32 is threaded into the bracket 33. The resilient assembly 24 is then placed between the free end of the bimetal element and the end of the adjusting screw and by varying the position of the end 31 of the adjusting screw, the end thrust of the coil spring 25 on the bimetal blade is adjusted.

Arranged adjacent the free end of the bimetal member 21 so as to be moved in accordance with the snap action movement thereof is a movable contact structure comprising a block 36 made of some suitable insulating material such as porcelain, on which is mounted a pair of bridging contact members 37 which in the preferred form of this invention consist of a layer of precious metal 38 firmly secured to a base metal 39 and to which a U-shaped bracket 40 is fixed by means of a bolt 41. In order to obtain a good electrical connection between the bridging contact members and the fixed contacts with which they are adapted to cooperate, the bridging contact members 37 are loosely mounted on the block 36 by means of pins 42. As shown in Figs. 3 and 4, the legs of the U-shaped bracket 40 extend outwardly from the block 36 and are spaced apart an amount sufficient to permit the bimetal member 21 to lie therebetween. Provided in each leg of the bracket 40 near the outer edge thereof is a slot 43 which is adapted to receive a laterally extending abutment or ear 44 integrally formed on each side of the bimetal member adjacent the free end thereof. By means of the engagement of the abutments 44 with the side walls of the slots 43, snap action movement of the bimetal member will be transmitted to the movable contact structure so as to cause it to move in response to the occurrence of a predetermined high temperature.

In order to support the movable contact structure in its operative position, there is provided a lever 45 which is pivotally mounted at 46 on a bracket 47 secured to the base plate 19 by

means of rivets 48. The lever 45 is channel-shaped over a portion of its length and the remainder thereof comprises a pair of spaced arms 49 which are adapted to lie on opposite sides of the bracket 40 and to be connected to the legs thereof. In order to insure substantially vertical movement of the contact structure relative to the base plate 19, a pivotal connection is provided between the arms of the lever 45 and the legs of the bracket 40. In effecting this pivotal connection, each arm 49 of the lever 45 is provided with a pin 50 which is adapted to be inserted in an opening 51 located in each leg of the bracket 40.

15 Arranged to cover the elements of the control device, is a housing 52 made of some suitable electrically insulating material such as porcelain. The housing 52 is adapted to lie within the flange 19a provided on the base plate 19 and is secured to the base plate 19 by means of a plurality of screws 53 which are adapted to be threaded into threaded openings 54 provided in the base plate. Firmly secured to the housing 52 by means of screws 55 is a plurality of fixed contact members 56 which are provided with terminal screws 57 for making electrical connections therewith. Each of the fixed contact members 56 has welded thereon remote from the terminal screws 57 contact tips 58 which in the 20 preferred form of our invention comprise a portion of precious metal, such as silver, secured to a backing portion, such as steel, which may be secured to the contact members 56 by welding. The bridging contact members 37 loosely mounted 25 on the member 36 are adapted to engage the contacts 58 and to close the circuit controlled thereby.

In order to reduce arcing between the fixed and movable contacts and to maintain the contacts in engagement until the bimetal element 40 has accelerated a sufficient amount to move quickly and with a snap action under the influence of the resilient member 24, a coil spring 59 has been provided and the slot 43 provided in 45 each leg of the bracket 40 is made wider than the width of the bimetallic strip 21. This construction permits the bimetallic member to move a slight amount without causing movement of the bridging contact carrying block 36 and also 50 permits the bimetal to accelerate under the influence of the spring 59 so that a kick is imparted to the bracket 40 upon the occurrence of the actuating temperature thereby causing a quick, sudden opening of the contacts.

55 In order to maintain the contact pressure between the bridging contacts and the fixed contacts while such small movements of the bimetal member take place, the coil spring 59 is located within the U-shaped bracket 40 so as to be between the bimetal blade and the member 36. The spring 59 is held in position at one end by the headed rivet 60 located in the bimetal element and at its opposite end by the head of the bolt 41. This spring member is relatively light in construction but is adapted to exert an upward force on the member 36 so that the movable contact members 37 are held in engagement with the fixed contacts 58 even though the thrust exerted by the resilient member 24 has been diminished due to slight movement to the left of the bimetal strip 21. With such a construction, wearing of the contacts is effectively diminished.

As previously stated, control devices suitable for use as over-temperature release switches

must be constructed so that the possibility of flashover is substantially non-existent. This means that the gap between the bridging contact members and the fixed contact members must be sufficiently wide to reduce the possibility of an electrical breakdown such as caused by lightning. In addition, an over-temperature release switch must be constructed so that the switch will not automatically reclose at any normal ambient temperature. Both of these conditions are satisfied in the control device of this invention by the assembly and initial adjustment of the device. To illustrate this more fully, the bimetal blade is initially assembled so that its knife edge moves equal distances above and below the normal switch center line which is an imaginary line drawn between the rounded end 31 of the adjusting screw and the point of attachment of the bimetal blade. Furthermore, the initial adjustment of the screw 32 is such that at some predetermined temperature, say 70° F., the switch will remain in either a closed or an open position and will exert the same force against the fixed contacts 58 as against the stop which is formed by the end of the bracket 40 engaging the base plate 19. By advancing the screw 32, the vertical component of the thrust of the spring 25 is increased until sufficient contact pressure is obtained between the fixed and movable contacts so that a temperature of a predetermined high value, say 200° F., will be necessary to cause the contacts to be opened. Since the switch moves equal distances above and below its center line, the difference of 130° F. between the initial temperature adjustment and the "release" temperature adjustment represents one-half the switch amplitude, the full amplitude being 260° F. With such an adjustment of the switch amplitude, the switch will open the circuit at 200° F. but will not reclose automatically so long as the temperature is above -60° F. With the switch moving equal distances above and below the center line, a wide operating gap is obtained which substantially removes the possibility of flashover once the contacts are opened.

It is to be observed that with our new and improved control device the temperature at which the device is adapted to be actuated is controlled by adjusting the position of the screw 32. With such a construction and arrangement, no additional adjusting means are required and once the adjustment has been made, the adjusting screw is locked in position by means of the lock nut 35. An opening 61 is provided in the end of the casing 52 to permit access to the screw 32 and a suitable cover 62 is provided to close this opening.

Since the control device is constructed and arranged so that it will not automatically reclose at normal ambient temperatures, it is essential to provide manual means for reclosing the contacts after they have been opened in response to the occurrence of the predetermined release temperature. In accordance with this invention the manual reclosing arrangement includes a reset plunger 63 which is loosely mounted in an opening 64 provided in the cover 52 opposite the end of the channel portion 65 of the lever 45. The reset plunger is provided with a head 66 which is adapted to engage the channel portion 65 of the lever and a coil spring 67 is arranged between the head of the plunger 63 and the shoulder 68 of the opening 64 to bias the plunger outwardly with respect to the cover 75

5 52. Upon the occurrence of the release temperature the bimetal element is snapped to the left as viewed in Fig. 3 and the lever 45 is pivoted counterclockwise causing the channel portion 65 to move adjacent the head 66 of the reset plunger 63. To reset the device, it is necessary only to press the plunger inwardly. The head 66 will engage the lever and rotate it in a clockwise direction an amount sufficient to cause 10 the control to be snapped to the closed position.

15 It is believed that the operation of our improved control device is apparent from the preceding detailed description. However, in further describing its operation, reference will be had to Fig. 5 in which the over-temperature control switch of this invention is shown applied in the control circuit for the two-element water heater shown in Fig. 1. With the exception of the provision of the over-temperature switch, the control circuit shown in Fig. 5 is substantially the same as that described and claimed in United States Letters Patent 1,892,557, granted December 27, 1932 on an application filed by Francis H. McCormick. Briefly, the circuit includes the heater elements 11 and 12 schematically represented. Arranged to control the energization of the heater elements are the temperature responsive members 69 and 70, more fully described in the aforementioned McCormick patent. The control member 69 is of the double-throw type and the circuit is such that the heater element 12 will not be energized until the control member 69 has operated to deenergize the heater element 11. Suitable leads are provided for connecting the elements to the fixed contacts of the over-temperature switch which contacts are in turn connected through a suitable line switch 71 to a suitable source of electrical supply 72. In order to simplify the showing in Fig. 5, only the moving elements of the over-temperature switch are illustrated but these are given the same reference characters as above.

40 45 In operation, with the over-temperature release switch in its circuit closing position, the line switch 71 is closed to connect the heater elements 11 and 12 to the electrical supply 72. The heater elements are then energized in accordance with the position of the control devices 69 and 70 as more fully described in the aforementioned McCormick patent and the water in the heater is brought to and maintained at a predetermined desired temperature. If for any reason either of the control devices 69 or 70 should fail to operate causing the heater elements to heat the water to a temperature which approaches the release temperature of the over-temperature switch, the bimetal element 21 of this switch will start to deflect to the left as viewed in Figs. 3 and 5. Due to the play provided between the bimetal element and the bracket 37, this initial movement of the bimetal element does not cause movement of the contact carrying member 36. Since the spring 59 biases the bridging contact carrying member 36 to the right, the contact pressure between the fixed and movable contact remains unchanged during this initial movement of the bimetal member even though the vertical component of the force exerted by the spring 25 on the end of the bimetal blade decreases with such movement. As the temperature continues to increase, the movement of the bimetal is accelerated and when the release temperature is reached in the heater tank, the abutments 44 on bimetal member 21 move 50 55 60 65 70 against the opposite edges of the slots 43 and

under the influence of the spring 25 cause the bridging contacts to be moved abruptly away from the fixed contacts 58, the extent of this movement being limited by the end of the bracket 40 coming into engagement with the surface of the base plate 19. Since the contacts are held in engagement by the action of spring 59 until they are kicked open by the rapid movement of the bimetal blade, creep action which might otherwise occur is substantially eliminated. Opening of the contacts 58 causes the supply circuit for both heater elements 11 and 12 to be opened thus preventing any further rise in temperature of the water. As previously described once the release switch is snapped open it will not automatically reclose at any normal ambient temperatures encountered in electric water heater installation. In order to reset the switch, it is necessary to press the reclosing button inwardly causing the lever 45 to be pivoted so that the switch will be snapped to the closed position. Prior to doing this, however, the operator will have examined the temperature control devices 69 and 70 to determine the cause of the over heating which actuated the over-temperature switch.

While we have shown a particular embodiment of our invention, it will be understood, of course, that we do not wish to be limited thereto since many modifications may be made and we, therefore, contemplate by the appended claims to cover any such modifications as fall within the true spirit and scope of our invention.

What we claim as new and desire to secure by Letters Patent of the United States is:

1. In an over-temperature release switch, a bimetallic temperature responsive member fixed at one end and having its opposite end free to move, pivotally mounted resilient means for engaging said free end of said bimetallic member to cause said member to move quickly and with a snap action, a bridging contact carrying member, a bracket secured to said contact carrying member, and means for loosely connecting said bimetallic member to said bracket so that said bridging contact carrying member is moved only in response to the snap action movement of said bimetallic member.

2. In an over-temperature release switch, a bimetallic temperature responsive member fixed at one end and having its opposite end free to move, resilient means for causing said bimetallic member to be actuated between two limiting positions quickly and with a snap action, switch means, means for transmitting the snap action movement of said bimetal member to said switch means, means for adjusting the temperature at which said bimetal member is moved with a snap action, said means being adjusted so that said switch means are moved to the open circuit position in response to the occurrence of a predetermined high temperature and are maintained in this open position for all normal ambient temperatures, and manual means for causing said bimetal strip to be moved with a snap action to effect resetting of said switch means.

3. In an over-temperature release switch, a bimetallic temperature responsive member fixed at one end and having its opposite end free to move, resilient means for causing said bimetallic member to be actuated between two limiting positions quickly and with a snap action, switch means, means for transmitting the snap action movement of said bimetal member to said switch means, means for adjusting the thrust exerted

by said resilient means on said bimetal strip to control the upper and lower temperatures at which said bimetal is moved with a snap action, said last mentioned means being adjusted so that the range between the temperature which causes said bimetal strip to move said switch means to the open circuit position and the temperature which causes said bimetal strip to move said switch means from the open circuit position to the closed position is such that once the switch means have been snapped to the open position they will not automatically reclose at normal ambient temperatures, and manual means for causing said bimetal strip to be moved with a snap action to effect a manual reclosing of said switch means at temperatures above said predetermined low temperature.

4. In a control device, a bimetallic strip fixed at one end and having its opposite end free to move, pivotally mounted resilient means adapted to engage said free end of said bimetallic strip to cause said strip to move with a snap action, switch means comprising a plurality of fixed contacts and a bridging contact assembly, a bracket secured to said bridging contact assembly, means for loosely connecting said bimetallic member to said bracket so that said bridging contact assembly is moved in accordance with only the snap action movement of the bimetal strip to cause said switch means to perform a controlling function, and resilient means for maintaining said bridging contact assembly against said fixed contacts during initial movement of said bimetal strip prior to its snap action movement which causes said bridging contact assembly to be moved away from said fixed contacts.

5. In a control device, a bimetallic temperature responsive member fixed at one end and having its opposite end free to move, resilient means engaging said free end of said bimetallic member to cause said member to be moved with a snap action, means for adjusting said resilient member to vary the temperature at which said bimetallic member is actuated, a bridging contact carrying member adapted to cooperate with fixed contacts to perform a controlling function, means including a slotted bracket for loosely connecting said bimetallic member to said bridging contact carrying member so that said bridging contact carrying member is moved only in response to snap action movement of said bimetal member, and resilient means biasing said bridging contact member against said fixed contacts so that the connection between said fixed and movable contacts is broken only when said bimetal member moves with a snap action.

6. In a control device, a bimetallic strip fixed at one end and having its opposite end free to move, resilient means engaging said free end of said bimetallic strip to cause said strip to be moved with a snap action, means for adjusting said resilient means to preselect the release temperature at which said bimetallic strip is actuated with a snap action, a bridging contact carrying member adapted to cooperate with the fixed contacts to perform a controlling function, means including a slotted bracket for loosely connecting said bimetallic member to said bridging contact carrying member so that the latter is moved only in response to snap action movement of said bimetal strip, and a coil spring lying between said bimetallic strip and said bracket to bias said bridging contact member against said fixed contacts so that the connec-

tion between the contacts is broken only when said bimetal member moves with a snap action.

7. In an over-temperature switch, a base plate, means for supporting a bimetallic strip on said base plate so that it is fixed at one end and free to move at the opposite end thereof, resilient means pivotally mounted on said base plate and adapted to engage the free end of said bimetal strip to cause it to be moved between two limiting positions quickly and with a snap action, means for adjusting said pivotal mounting to control the temperature at which said bimetal strip is moved with a snap action, a cover mounted on said base plate, stationary contacts mounted on said cover, a bridging contact assembly arranged to engage said stationary contacts, a bracket mounted on said bridging contact assembly and loosely connected to said bimetal strip so that said contact assembly is moved only in accordance with the snap action movement of said bimetal strip, and separate resilient means lying between said bimetal strip and said contact assembly for biasing said bridging contacts against said fixed contacts so that the contact pressure between said contacts remains unchanged until said bimetal strip is moved with a snap action.

8. In an over-temperature switch, a base plate, means for supporting a bimetallic strip on said base plate so that it is fixed at one end and free to move at its opposite end, a spring pivotally mounted on said base plate and adapted to engage the free end of said bimetal strip to cause it to be moved between two limiting positions quickly and with a snap action, a cover mounted on said base plate, a plurality of stationary contacts mounted on said cover, a bridging contact carrying member pivotally mounted on said base plate so as to move substantially perpendicular to said base plate, means for transmitting the snap action movement of said bimetal member to said bridging contact carrying member, said means comprising a bracket mounted on said bridging contact carrying member and having a pair of slots adjacent the ends of the legs thereof and a pair of abutments on said bimetal member arranged to engage the edges of said slots, said slots having a width greater than the thickness of said bimetal so that said bimetal may be moved a small amount prior to its snap action movement without causing movement of said contact carrying member, and resilient means engaging said bimetal member and said bracket and adapted to bias said contact carrying member against said fixed contact so that the contact pressure between these contacts is unaffected by small movements of said bimetal member relative to said contact carrying member.

9. In an overtemperature switch, a base plate, means for supporting a bimetallic strip on said base plate so that it is fixed at one end and free to move at its opposite end, a spring pivotally mounted on said base plate and adapted to engage the free end of said bimetal strip to cause it to be moved between two limiting positions quickly and with a snap action, switch means having a portion pivotally mounted on said base plate, means for transmitting the snap action movement of said bimetal member to said pivoted portion of said switch means to cause said

switch means to be actuated between a closed and open circuit position, means for adjusting the temperature at which said bimetal member is moved with said snap action, said means being adjusted so that said switch means are moved to the open circuit position in response to the occurrence of a predetermined high temperature and are maintained in this open circuit position for all normal ambient temperatures, a cover mounted on said base plate, and manual means adapted to engage said pivotally mounted portion of said switch means to reset said switch means after it has been moved to said open circuit position, said manual means extending through said cover so as to be operable from the exterior thereof.

10. In an overtemperature switch, a base plate, means for supporting a bimetallic strip on said base plate so that it is fixed at one end and free to move at its opposite end, switch means having a portion pivotally supported on said base plate, means for transmitting movement of said bimetallic member to said switch means to cause said switch means to be actuated between a closed and an open circuit position in accordance with temperature changes, means for effecting movement of said switch means with a snap action, means for adjusting the temperature at which said switch means is moved from one circuit controlling position to the other, said means being adjusted so that said switch means are moved to the open circuit position in response to the occurrence of a predetermined high temperature and are maintained in this open circuit position for all normal ambient temperatures, a cover on said base plate, and manual means adapted to engage said pivotally mounted portion of said switch means to reset said switch means after it has been moved to said open circuit position, said manual means being operable from the exterior thereof.

11. In an overtemperature switch, a casing including a base plate and a cover, a plurality of fixed contacts on said cover, bridging contact means adapted to cooperate with said fixed contacts to perform a circuit controlling function, an arm secured to said bridging contact means, means for pivotally mounting said arm within said casing, temperature responsive means adapted to engage said arm to cause pivotal movement thereof and actuation of said bridging contact means between a closed and open circuit position in accordance with temperature changes, resilient means for effecting movement of said bridging contact means quickly and with a snap action, means for adjusting the temperature at which said contact means is moved from one circuit controlling position to the other by said temperature responsive means, said means being adjusted so that said switch means are moved to the open circuit position in response to the occurrence of a predetermined high temperature and are maintained in said open circuit position for all normal ambient temperatures, and manual means operable to reset said switch means after it has been moved to said open circuit position, said means being actuated from the exterior of said casing.
